Inventor:

Frank C. Watson,
Orwig & Bair, Attks.

UNITED STATES PATENT OFFICE.

FRANK C. WATSON, OF DES MOINES, IOWA.

CARBURETER.

1,044,314.

Specification of Letters Patent. Patented Nov. 12, 1912.

Application filed February 5, 1912. Serial No. 675,667.

To all whom it may concern:

Be it known that I, FRANK C. WATSON, a citizen of the United States, residing at Des Moines, in the county of Polk and State 5 of Iowa, have invented a new and useful Carbureter, of which the following is a specification.

The object of my invention is to provide a carbureter of simple, durable, and inexpensive construction, provided with means whereby a uniform richness of mixture is maintained.

More particularly, it is the object of my invention to provide a carbureter, in which the relative amount of gasoline vapor and air may be manually regulated and provided with means whereby the suction from the engine automatically maintains a uniform richness of mixture by increasing or decreasing the amount of air and gasoline vapor delivered to the mixture chamber.

A further object of my invention is to provide a carbureter whereby the relative proportions of gasoline and air may be regulated and uniformity of mixture maintained without the use of a needle valve or a float.

A further object is to provide a carbureter having an air pressure chamber connected with the intake tube for maintaining a uniform pressure on the inflowing gasoline.

My invention consists in certain details, in the construction, arrangement and combination of the various parts, whereby the objects contemplated are attained, as hereafter more fully set forth, pointed out in my claims, and illustrated in the accompanying drawings, in which—

Figure 1 shows a vertical, central, sectional view through a carbureter embodying my invention. Fig. 2 shows a sectional view on the line 2—2 of Fig. 1, and Fig. 3 shows a detail sectional view of some of the parts of my improved carbureter.

In the accompanying drawings, I have used the reference numeral 10 to indicate the body of the carbureting chamber of a carbureter, which is substantially cylindrical in form. Above the body 10 is a detachable 50 top portion 11. At one side of the body 10 is a discharge opening 12, in which is a throttle valve 13 of ordinary construction. In the lower end of the body 10 is an air intake tube 14. At one side of the body is 55 a casing 15 of suitable form to receive the parts hereinafter described. Connecting the

intake tube 14 with the interior of the casing 15, is a passage way 16. In the top 11 is a screw threaded opening in which is mounted a screw 17, on the outer end of which is a head 18. In the inner end of the screw 17 is a longitudinal opening or recess 19. The intake tube 14 extends within the carbureter body 10 to a point above the bottom wall 20 of the body 10. Resting on the upper end 60 of the intake tube 14 is an umbrella shaped valve 21 having a circumferential downwardly extending flange 22 outside the tube 14, extending at an acute angle from the upper end thereof. The valve 21 may be 65 varied in form if desired.

Slidably mounted in the lower end of the opening 19 is the upper end of a rod 23, the lower end of which is secured to the valve 21. Upon the valve 21 is a central downwardly extending lug 24. Between the lower end of the screw 17 and the upper side of the valve 21 is an extensible coil spring 23a. Mounted within the casing 15, is a lever 25, a portion of which extends through the 75 opening 16 to a point below the lug 24. A link 26 is pivoted to the end of the lever 25 and to the lug 24. The other end 27 of the lever 25 is forked as shown in Fig. 3. Slidably mounted in the casing 15 so as to be 80 capable of horizontal sliding movement, is a fulcrum 28, which rests beneath the forked portion 27 of the lever 25. The fulcrum 28 is provided with a screw threaded, longitudinal opening in which is mounted a screw 29, which extends to a point outside the 85 casing 15 and is provided at its outer end with a head 30. The screw 29 is rotatably mounted in the wall of the casing 15 and I fix washers 31 on the screw 29 on each side 90 of said wall. In the upper portion of the casing 15 near the body 10, is a screw threaded opening in which is mounted a screw 32 on which is a head 33. The inner end of the screw 32 is provided with a longitudinal recess or opening 34. Pivottally secured to the lever 25 is a rod 35, the upper end of which is slidably received in the opening 34. Between the lower end of the screw 32 and the lever 25 is mounted an extensible coil spring 36 on the rod 35.

The lever 25, the fulcrum 28, the rod 35, and the spring 36 are so arranged that the weight of one end of the lever 25 tends to draw said lever downwardly. The lever is 100 held in position resting upon the fulcrum 28, by said fulcrum, and by the link 26, se-

cured to the lug 24 on the valve 21. The lower part of the casing 15 is provided with a downwardly extending portion 37 forming a chamber 38, the sides of which are inclined downwardly to a lowest point at one side of said chamber. Below the downwardly extending portion 37, at one side from the lowest point thereof, is an air pressure chamber 39. Communicating with the lower part of the chamber 39 is a gasoline intake tube 40. A tube 41 extends from a point within the chamber 38 through the lower wall thereof at a point above the lowest part of said wall to the lower part of the interior of the chamber 39, as shown in Fig. 1. The upper part of the tube 41 forms a valve seat. Resting upon the upper end of the tube 41 is a valve 42. A rod 43 extends upwardly from the valve 42 between the sides of the forked end 27 of the lever 25 to a point near the top or upper end of the casing 15. Fixed on the rod 43 just above the arms of the forked portion 27, is a washer 44. In the upper end of the casing 15, is a screw threaded opening in which is mounted a screw 45, on which is a head 46. The screw 45 and the rod 43 are located farther away from the body 10 than the screw 32 and the rod 33. In the lower end 30 of the screw 45 is a central, longitudinal opening 47 in which is slidably mounted the upper end of the rod 43. Between the lower end of the screw 45 and the washer 44 is an extensible coil spring 48. A gasoline intake tube 49 extends from a point at the lower part of the interior of the mixing chamber in the body 10 through the wall of the body 10 to a point near the lower part of the chamber 38.

40 The parts hereinbefore described, are so arranged that in practical operation, they operate in the following manner: Gasoline from the supply tank flows through the tube 40 into the air pressure chamber 39. As soon as the gasoline reaches the level of the lower end of the tube 41, the air in the chamber 39 will begin to be compressed, forming a cushion within said chamber. The gasoline then flows upwardly through the valve 42. As the engine is operated, the suction through the tube 12 and the carbureting chamber within the body 10, tends to slightly raise the valve 21. By the upward movement of the valve 21, the lever 25 is slightly raised on the fulcrum 23, thereby raising the washer 44, the rod 43 and the valve 42, allowing a small amount of gasoline to flow into the chamber 38. As the engine runs, gasoline is drawn through the tube 49 and air is drawn through the tube 14 with each stroke of the pistons. If the engine runs more rapidly, and the suction through the tube 12 becomes stronger, the valve 21 is raised to a higher point and a larger amount of air is admitted to the mix-

ing chamber in the same length of time, than before. The valve 42 is also raised higher and more gasoline flows into the chamber 38 in the same period, than before. On the other hand, as the engine runs more rapidly, the length of time of suction through the tube 12 is shorter and the period of time during which the valves 21 and 42 are raised is shortened. It therefore appears that the amount of gasoline and vapor and air taken into the cylinders each time, remains the same. The richness of the mixture also remains approximately uniform, for the reason that the air inlet valve and the gasoline inlet valve work in unison. Whenever it is desired to increase the amount of gasoline delivered to the mixing chamber or to decrease the same, with relation to the amount of air taken in, the fulcrum 28 is moved closer to or farther from the end of the lever 25 by means of the screw 29. The richness of the mixture having once been fixed by the proper location of the fulcrum 28, will then be automatically maintained and the amount of air and gasoline drawn into the mixing chamber at each piston stroke will remain the same. By means of my air pressure chamber 39, I maintain pressure for causing a quick flow of gasoline through the tube 41 whenever the valve 42 is raised.

It will be readily seen that a large number of variations may be made in details of construction of my improved carburetor, without departing from the essential features of my invention.

The advantages of my carburetor are seen in the foregoing description. The richness of the mixture, or in other words, the relative proportions of air and gasoline vapor, may be determined by experiment, by moving the fulcrum 28 and when the proper mixture is once secured, the arrangement and construction of the parts of my carburetor are such that a uniform mixture may be maintained. It will be seen that my spring 23^a serves to hold the valve 21 seated and also to limit the upward movement thereof. The spring 48 is extremely sensitive and holds the valve 42 properly seated. The spring 33 yieldingly holds the lever 25 at the lower position of its movement, and assists the spring 23^a to return the said lever to its lower position after each charge is taken into the engine.

I claim as my invention:

1. In a device of the class described, a carbureting chamber, an outlet tube communicating therewith, an air inlet tube extending into said carbureting chamber through the lower wall thereof, a chamber for receiving gasoline, a tube extending from a point near the lowest part of said last named chamber to the interior of said carbureting chamber, a gasoline intake tube

extending into the interior of said gasolene receiving chamber, valves for closing the inner ends of said intake tubes, means for normally holding said valves seated, a lever operatively connected with both valves so that when the valve on the air inlet tube is raised, the valve of the gasolene inlet tube is raised in unison.

2. In a device of the class described, a carbureting chamber, an outlet tube communicating therewith, an air inlet tube extending into said carbureting chamber through the lower wall thereof, a valve resting on the inner end of said air inlet tube, and yielding means for normally holding said valve in its seated position, a casing adjacent to said carbureting chamber, the interior of which communicates with said air inlet tube and has a downwardly extending portion designed to receive gasolene, a tube extending from a point near the bottom of said downwardly extending portion to the interior of said carbureting chamber, a gasolene inlet tube extending to a point in the interior of said casing near the bottom of the downwardly extending portion thereof, a valve for closing the inner end of said gasolene inlet tube, a fulcrum slidably mounted in said casing, a lever resting upon said fulcrum near one end and operatively connected with said first valve at the other end, means whereby the raising of said lever raises said second valve, yielding means for holding said second valve in its seated position, and yielding means for holding said lever at the lower position of its movement.

3. In a device of the class described, a carbureting chamber, an outlet tube communicating therewith, an air inlet tube extending into said carbureting chamber through the lower wall thereof, a valve resting on the inner end of said air inlet tube, and yielding means for normally holding said valve in its seated position, a casing adjacent to said carbureting chamber, the interior of which communicates with said air inlet tube and has a downwardly extending portion designed to receive gasolene, a tube extending from a point near the bottom of said downwardly extending portion to the interior of said carbureting chamber, a gasolene inlet tube extending to a point in the interior of said casing near the bottom of the downwardly extending portion thereof, a valve for closing the inner end of said gasolene inlet tube, a fulcrum slidably mounted in said casing, a lever resting upon said fulcrum near one end and operatively connected with said first valve at the other end, means whereby the raising of said lever raises said second valve, yielding means for holding said second valve in its seated position, and yielding means for holding said lever at the lower position of its movement,

70
said second named yielding means being located between said fulcrum and said first valve and said last named yielding means being located between said second yielding means and said first named valve.

4. In a device of the class described, a carbureting chamber, an outlet tube communicating therewith, an air inlet tube extending into said carbureting chamber through the lower wall thereof, a valve resting on the inner end of said air inlet tube, yielding means for normally holding said valve in its seated position, a casing adjacent to said carbureting chamber, the interior of which communicates with said air inlet tube and has a downwardly extending portion designed to receive gasolene, a tube extending from a point near the bottom of said downwardly extending portion to the interior of said carbureting chamber, a gasolene inlet tube extending to a point in the interior of said casing near the bottom of the downwardly extending portion thereof, a valve for closing the inner end of said gasolene inlet tube, a fulcrum slidably mounted in said casing, a lever resting upon said fulcrum near one end and operatively connected with said first valve at the other end, means whereby the raising of said lever raises said second valve, yielding means for holding said second valve in its seated position, and yielding means for holding said lever at the lower position of its movement,

washer on said stem above said lever, whereby said stem is raised when said lever is raised, yielding means for holding said second valve in its seated position, and yielding means for normally holding said lever in position where one end of said lever rests upon said fulcrum, and said first valve rests in its seated position.

6. In a device of the class described, a carbureting chamber, an air inlet tube extending through the lower wall thereof into the interior of said carbureting chamber, a valve normally resting on the inner end of said air inlet tube, a casing adjacent to said carbureting chamber, the interior of which communicates with said air inlet tube, said casing having a downwardly extending portion, a tube extending from a point near the

bottom of said downwardly extending portion to the interior of said carbureting chamber, a gasoline inlet tube extending into the interior of said casing to a point above the bottom of the downward extension thereof, a valve normally resting upon the upper end of said gasoline inlet tube, a discharge tube communicating with said mixing chamber and means whereby when said first valve is raised by suction from the engine, said second valve will be raised in unison with the first valve.

Des Moines, Iowa, January 15, 1912.

FRANK C. WATSON.

Witnesses:

BESS E. DEAL,
MARY WALLACE.
